UNITED STATES PATENT OFFICE.

OREA M. KELLEY, OF LOWELL, MASSACHUSETTS.

AERIAL BOMB.

1,330,191.

Specification of Letters Patent. Patented Feb. 10, 1920.

Application filed November 3, 1917. Serial No. 200,219.

To all whom it may concern:

Be it known that I, OREA M. KELLEY, a citizen of the United States, residing at Lowell, Middlesex county, and State of Massachusetts, have invented and discovered certain new and useful Improvements in Aerial Bombs, of which the following is a specification.

This invention relates to torpedoes and 10 more particularly to the class known as self-propelled aerial bombs and its object is to provide a device capable of being launched under its own power from any simple inclined track structure without requiring a 15 specially constructed launching stand. Another object is to construct such a device with self-contained propelling means and also with a device for stopping the propelling means and retarding the flight of the 20 projectile at a predetermined point. Another object is to construct a device to be light in weight and free from any complicated operating devices.

With these and other objects in view, the 25 invention consists of a combination and arrangement of parts as described in the specification and particularly pointed out in the appended claims, reference being had to the accompanying drawings in which like 30 characters represent similar parts in the several views. In said drawings—

Figure 1 is a side elevation of the aerial torpedo shown at the angle of flight,

Fig. 2, a top plan view thereof, and

Fig. 3, an enlarged horizontal sectional view on the dotted line 3—3 in Fig. 1.

In structure my invention consists of a body portion 10 divided by the partition 11 into an explosive chamber 12 and a driving mechanism chamber 13. The chamber 12 contains an explosive charge 14 capable of being ignited by means of a percussion cap 15 through the medium of a rod 16 mounted in the front end of the body, on coming in contact with any object. The body portion 10 is provided on each side with a supporting wing or plane 17 slightly curved to overcome the gravity of the device while in flight and provided at their extreme corners 15 with rollers 18 adapted to run on the inclined rails (indicated by dotted line 100 in Fig. 1) of any suitable launching track that may be provided. The launching is accomplished by means of the propelling device 20 located in the chamber 13 and consists of a source of energy 19 from which leads

one wire 20 to one side 21 of a controlling switch located within the chamber and having a handle 22 projecting through the chamber within reach of the operator. A 60 wire 23 leads from the handle 22 to one side of an electric motor 24 from which leads a wire 25 which is in circuit with one side 26 of a circuit breaker. The other side 27 thereof is connected by means of a wire 28 65 to the source of energy.

The motor 24 is provided with a shaft 29 having mounted thereon a gear 30 meshing with a similar gear 31 formed integral with a sleeve 32 which is slidably keyed to the 70 propeller shaft 33 journaled at one end in a bearing 34 and at the other end in a sleeve 35 and which also has secured thereto an aerial propeller 36. The sleeve 32 is formed with a cone shaped recess 37 adapted to be 75 brought into contact with a stationary cone member 38 formed integral with the bearing 34 and also formed with a circumferential groove 39 in which operate a pair of rollers 40 carried by a yoked lever 41 which is fulcrumed at 42 to the body 10. The opposite end from the fulcrum is flattened to be engaged by a spring pressed hook 43 forming part of a bell-crank lever having an arm 44 for a purpose to be explained later. The 80 lever 41 is held by the hook 43 against the tension of a spring 45. It will thus be understood that when the contact switch 21 is closed, the current from the battery 19 will operate the motor 24 and through the gears 85 30 and 31, will impart the motion to the propeller 36 thereby exerting enough force to launch the device and also drive it through the air until a desired point in its 90 flight has been reached. At this point it is 95 desired to suddenly check the advancing of the flight and cause the torpedo to drop vertically. I have accomplished this by means of a clock work 46 comprising a train 100 of gears, the highest speed one having 105 mounted on its spindle 47 a speed retarding fan 48 prevented from rotating by means of a lever 58 and on the spindle 49 of one of the low speed gears, a pinion 50 meshing with a rack-bar 51 mounted to slide in bearings 52 and provided with a series of perforations 53 which may be spaced so as to represent certain intervals of time, for example five seconds. A pin 54 is inserted in either of the perforations, predetermined, 110 and so located that when the rack-bar 51 is moved along it will come in contact with the

arm 44 causing the arm 43 to release the end of the lever 41 and thereby allowing the spring 45 to swing the lever which movement simultaneously disengages the gears 5 30 and 31, breaks the electric circuit between the contact members 26 and 27 and arrests the motion of the propeller by means of the clutch members 37 and 38, thereby causing the torpedo to drop vertically, it 10 being guided at all times by the fixed vertical and horizontal fins, or guiding vanes 55.

It is thought that with the above description, anyone skilled in the art may readily understand and operate the device, however 15 I wish it understood that my invention is not confined to the exact structure shown and described, as changes in its form, proportions and minor details may be resorted to without departing from the spirit or 20 sacrificing any of the advantages of the invention.

What I claim is:

1. An aerial torpedo of the class described comprising a two compartment body portion, supporting and steering planes secured thereto, a propeller shaft, a motor, gears connecting said motor and said shaft, a clutch member formed integral with the gear on the propeller shaft, a bearing for 25 said shaft, a stationary clutch member formed integral with said bearing, a lever for operating said integral gear and clutch member to suddenly arrest motion of said shaft, and means for releasing and operating said lever, substantially as described.

2. An aerial torpedo of the class described comprising a body portion, supporting and

steering planes secured thereto, a propeller shaft, a propeller on said shaft, a sliding gear on said shaft, a clutch element formed 40 integral with said gear, a motor driving said gear, a bearing for the propeller shaft, a clutch element formed integral with said bearing, a lever for operating said integral clutch and gear, a spring for operating said 45 lever, a detent for holding said lever, and means for operating said detent, substantially as described.

3. In an aerial torpedo of the class described, the combination of a body portion, 50 supporting and steering planes secured thereto, a propeller, means for stopping said propeller consisting of a clutch composed of a stationary member and a sliding and revolving member, a lever operating said 55 sliding member, a spring to operate said lever, a detent for holding said lever, means for operating said detent consisting of a spring motor, a pinion on one of the shafts of said motor, a rack for meshing with said 60 pinion, spaced perforations in said rack, a pin adapted to be inserted in either of said perforations, and an arm connected with said detent and adapted to be engaged by said pin to release said lever, substantially 65 as described.

In witness whereof, I have hereunto set my hand and seal at Lowell, Massachusetts, this 27th day of October, A. D. nineteen hundred and seventeen.

OREA M. KELLEY. [L. S.]

Witnesses:

JOHN A. PRATT,
ELIZABETH PRATT.
